UNITED STATES PATENT OFFICE.

HENRY DOERING, CHARLES DOERING, JR., AND MAX DOERING, OF CHICAGO, ILLINOIS.

LIQUID COOLING AND DISPENSING APPARATUS.

1,337,206.

Specification of Letters Patent. Patented Apr. 20, 1920.

Application filed April 5, 1915, Serial No. 19,299. Renewed September 5, 1919. Serial No. 321,961.

To all whom it may concern:

Be it known that we, HENRY DOERING, CHARLES DOERING, Jr., and MAX DOERING, citizens of the United States, residing at 5 Chicago, in the county of Cook and State of Illinois, have invented certain new and useful Improvements in Liquid Cooling and Dispensing Apparatus, of which the following is a description, reference being had to 10 the accompanying drawings, which form a part of our specification.

Our invention relates to an apparatus for cooling and dispensing liquids, provided with a removable container or bottle where- 15 in the liquid, such as mineral or distilled waters, and the like, are originally placed at the source of supply, and the container or bottle adapted to be inserted into place on our improved apparatus so as to enable the 20 liquid or water to be drawn therefrom as required.

The object of our invention is to provide a sanitary construction enabling the withdrawal of water directly from the original 25 container or bottle without permitting the portions of the container or bottle, which come into contact with the hands of the manipulators, to contact with the fluid or water, or with the portions through which 30 the water passes; the construction being such that dirt or other extraneous matter cannot find its way into the liquid or water.

Another object of our invention is to pro- 35 vide a construction wherein the original container or bottle will be provided with an automatic valve, which will permit the container or bottle to be inverted into place without permitting any leakage of the 40 liquid while the original container or bottle is put into place, or during the displacement of one container or bottle by another before the displaced container or bottle has been completely emptied. Our improved con- 45 struction is such, however, that proper plac- ing of the original container or bottle will result in the opening of an automatic valve, and permit the liquid or water to flow from the original container or bottle into the 50 cooling chamber until its capacity has been reached and as the liquid or water is being dispensed or withdrawn from time to time.

Another object of our invention is to provide an apparatus of the class specified 55 wherein the water resulting from the melting ice may drain from the cooling chamber

without, however, permitting air to enter the chamber to affect the temperature therein.

Another object of our invention is to pro- 60 vide a construction wherein the operation of the faucet for the purpose of withdrawing the liquid will automatically permit sufficient air to enter the apparatus, or rather the water-containing chamber, in order to 65 permit a proper flow of the liquid.

Another object of our invention is to pro- 70 vide a second compartment into which the drip from the faucet, as well as the drain from the cooling chamber, may be received; 75 the invention possessing other advantages inherent in the construction, which will be readily comprehended from the following detailed description of the drawings where- in:—

Figure 1 is a vertical sectional view of our improved apparatus illustrating an original container or bottle, with a portion broken away, while the liquid-receiving chamber and its connections are shown in 80 full lines.

Fig. 2 is a rear side elevation of the ap- 85 paratus, with the slide-door in the lower compartment shown open, and the compartment shown provided with an additional original container or bottle.

Fig. 3 is a cross-sectional view taken on the line 3—3 of Fig. 1 looking downwardly and the storage compartment provided with an original container or bottle, as illustrated 90 in Fig. 2.

Fig. 4 is a detail view in longitudinal sec- 95 tion, of the faucet and its connections.

Fig. 5 is a plan view of our improved stopper and valve showing the end which is 95 adapted to be inserted in the original container or bottle.

Fig. 6 is a vertical sectional view thereof.

Fig. 7 is a detail view of the upper end 100 of the tube or spout of the water-receiving chamber.

Fig. 8 is a detail view of the same mem- 105 ber looking at a different side.

Fig. 9 is a detail perspective view of the seal-member for the cooling chamber drain.

Fig. 10 is a longitudinal sectional view of 105 said member shown secured to the lower end of the drain-tube, illustrating the manner of forming the seal.

Fig. 11 is a top plan view of the water- 110 receiving chamber or member located with- in the cooling chamber.

In the particular exemplification of our invention, the main or body portion 15 of the apparatus, which is made of suitable material, such as sheet metal, and the like, is divided into separate compartments; the upper compartment 16 constituting the cooling chamber, while the lower compartment 17 constitutes a storage chamber.

The cooling chamber is preferably formed

- 10 by providing an inner wall 18 suitably spaced apart from the outer wall of the body portion so as to provide an intermediate space to be provided with suitable material, as shown at 19, of indifferent or non-heat conducting character; the inner wall 18 being extended throughout the upper chamber or compartment so as to completely insulate said chamber. The outer and inner walls of the cooling chamber are provided
- 15 with registering openings to receive a cover-member or lid 20, see Fig. 1, which is preferably made with a depending wall so as to contain suitable non-heat conducting material, as indicated; the opening being of
- 20 suitable size to permit the cooling chamber 16 to be charged with ice. The top of the cooling chamber or compartment is provided with another opening to receive the cup-shape member 21, which is provided with
- 25 the depending portion 21^a, adapted to extend a distance into the cooling chamber 16; the depending portion 21^a being of sufficient depth to receive the neck of an inverted original container or bottle 22 so as to permit the container of bottle 22 to rest on the flared rim or saucer-shape portion of the member 21. The bottom of member 21 is provided with a central opening adapted to receive the upwardly projecting tube or
- 30 spout 23 formed on the extension 24 of the water-receiving member or vessel 25. In order to prevent accidental displacement of member 21, we prefer to surround the opening in the lower part thereof with a shoulder or flange 26 adapted to receive the set-screw 27, whereby member 21 may be clamped to the outwardly presented tube or spout 23.

The water-receiving chamber or member

- 35 25 is preferably provided with the brackets 28 whereby the vessel or member 25 will be held a sufficient distance above the bottom of the cooling member, thereby not only permitting the cooling agent to completely surround the chamber or member 25, but also permitting proper drainage of cooling chamber 16 through the downwardly presented drain-tube 29. The drain-tube 29 extends through the lower wall of the upper compartment and into the upper part of the lower chamber or compartment 17, and has its lower end provided with a flange 30, which is intended to be received between the ledges or flanges 31 and 32 of the seal-member 33, shown in Figs. 1, 9 and 10. The

member 33 is made of greater depth at the point where it receives the tube or pipe 29; while the unattached end is provided with an upwardly sloping bottom, as shown at 33^a, terminating in the lip-portion 33^b 70 whereby the overflow from seal-member 33 will be directed or discharged into vessel 34 located in the compartment 17, as shown in Fig. 1.

The inner wall 18 of the cooling chamber 75 16 is preferably provided with the angle member or bracket 35, see Fig. 1, which is adapted to overlap the member or bracket 36 secured to the rear of vessel or member 25 when the latter has been properly put into 80 place, so as to prevent upward movement of vessel or member 25 when the original container or bottle is lifted off of member 21.

The forward portion of vessel or member 25 is provided with a suitable discharge tube 85 or pipe 37 arranged to extend through a suitable opening in both walls of the cooling chamber; the tube or pipe 37 being preferably screw-threaded, as shown in Fig. 4, so as to not only be removably secured in vessel or member 25, but also to receive the faucet 38 which is preferably screwed thereon, as shown in Fig. 4. The tube or pipe 37 is preferably provided with a shoulder or flange 37^a in order to effect a tight connection with the wall of the apparatus. The tube or pipe 37 has an inner wall or diaphragm 37^b formed so as to provide a passage 39, see Fig. 4, which is merely open at the forward or faucet end. The outer or 90 faucet end of the tube or pipe 37 constitutes a seat for a valve 40, which latter is provided with a stem 41 surrounded by coil spring 42, whereby the valve is normally held on its seat. The outer end of stem 41 100 is provided with a suitable handle 43, pivotally secured thereto, and having its fulcrum or bearing point on the faucet 38 at the point 44, so that downward pressure on handle or lever 42 will cause the pivoted end 105 thereof to move valve 40 from its seat. The faucet 38 is also provided with an air inlet or port 45 at a point in close proximity to the open end of passage 39, whereby air is permitted to flow through port 45 and into 110 passage 39 when the valve 40 is removed from its seat. The inner end of passage 39 communicates with a tube or pipe 46, located within the cooling chamber, and extends preferably along the side of member 115 or chamber 25, and connects with the upper portion of the extension 24, as shown in Fig. 1.

The tube or spout 23 extends slightly into extension 24 so that an air chamber will be 120 formed in the upper part of extension 24 after the liquid has risen in extension 24, so as to cover the lower end of tube 23. This accumulated air will prevent the liquid or water entering tube 46; the quantity of air 125 130

in the upper part of extension 24 being supplied by tube 46 with each operation of the faucet.

After the container or bottle 22 has been filled at the source of supply, it is provided with the stopper 47, made of suitable resilient material, impervious to water, such as rubber. The stopper is preferably provided with a tapered portion 47^a adapted to snugly fit within the orifice of the container or bottle 22, and with a shoulder or flange 47^b adapted to fit snugly onto the neck or spout of container or bottle 22, as shown in Fig. 1, so as to provide a fluid-tight connection.

The stopper 47 is provided with a passage 47^c extending longitudinally therethrough, see Fig. 6, the one or outer end whereof may flare, as shown, so as to enable the spout or tube 23 to readily enter the passage 47^c.

The other or inner end of the passage 47^c is provided with a valve 48, of hard rubber or other suitable material, retained or hingedly secured in place by member 49, which is pivoted to the staple 50, whose prongs or legs are suitably embedded in the plug or stopper, as shown in dotted lines in Fig. 6. Pivotal secured on the valve 49 is a substantially U-shape member 51, see Fig. 5, the upwardly presented legs or portions whereof are each provided with coiled springs 52. The upper ends of the springs 52 bear against the looped or encircling portions of rods or members 53, 53, suitably embedded in the plug or stopper 47, as shown in dotted lines in Fig. 6. The looped or encircling portions of members 53 receive the upper ends of the U-shape member 51. It is apparent from the construction shown and described that springs 52 normally maintain the valve 48 on its seat, thus closing passage 47^c against the flow of liquid therethrough.

The upper part of tube 23 is preferably provided with the extended converging portions or fingers 23^a, 23^a, arranged diametrically opposite each other, thereby providing sufficient space to the sides thereof. These portions or fingers 23^a are preferably bowed, as shown, and provide a sliding contact with the under side of valve 48, when the container or bottle 22 is put into place. The tube 23 is made to extend into member 21 a sufficient distance to enable the fingers 23^a to push valve 48 upwardly against the action of springs 52, 52, when the container or bottle 22 is seated on the rim of the member 21, as shown in Fig. 1.

With container or bottle 22 in place as described, it is evident that the liquid will be permitted to flow out of bottle 22 down through tube 23, into extension 24 and thence into receiving-chamber or member 25; a sufficient quantity of air being permitted to flow into container or bottle 22 to permit proper flow therefrom. As soon

as the water or liquid has filled chamber 23 and extension 24 it ceases to flow from container or bottle 22. As faucet 38 is operated to withdraw water, air is permitted to flow into the upper part of extension 24, 70 and thence into bottle 22 by means of tube 23, in sufficient quantities to equalize the pressure and cause a proper flow of the water or liquid.

The water or liquid-entering chamber or 75 member 25 will be cooled by the ice in chamber 16; the withdrawn water being immediately replaced by flow from container or bottle 22.

In order to protect the upper wall of 80 chamber or member 25 from injury by the ice falling thereon, we have shown the top provided with a corrugated plate 54, which may be formed so as to fit about extension 24, and be suitably held in place. 85

In vertical alinement with faucet 38, and at a point beneath the bottom of cooling compartment or chamber 16, we provide the wall of the body 15 with an opening or slot 55, see Fig. 1, about which we secure a drip-cup 56, adapted to receive the drip from faucet 38 during operation thereof.

As our improved apparatus is especially adapted to the use of sanitary or collapsible paper cups, we provide the cup-portion 56 95 with an incline 56^a, extending slightly through the slot or opening 55 in the wall of the apparatus, so as to not only direct the water dripped thereon, but also the discarded or used collapsed cups into the receptacle 34, removably set in compartment 17 of the apparatus. 100

As the body of our improved apparatus is shown as preferably made cylindrical, we show one wall of receptacle 34 curved to 105 conform to the wall of the body, to permit proper placing of the receptacle, as is more clearly shown in Fig. 3. The bottom of compartment 17 may also be provided with suitable lugs or stops, as shown at 57, see 110 Figs. 1 and 3, which insure the proper placing of receptacle 34.

The compartment or chamber 17 is of a size sufficient to receive an extra container or bottle 22^a, to replace container or bottle 22 when the latter has become empty, at which time the empty bottle 22 may be stored in chamber 17, out of the way. The rear wall of the main body 15 is provided with an opening, as shown in Fig. 2, sufficiently large to permit the bottle 22^a to be readily passed therethrough, as well as vessel or receptacle 34. The opening is preferably closed by the sliding door 58 which is bowed to conform to the curvature of the 115 wall of body 15, and slides along the inside of the wall or body 15, being held in proper sliding position by the rail 59, secured at the top, and rail 60, secured at the bottom of chamber 17, as shown in Figs. 1 and 3. 120 125 130

In order to permit access to the upper or cooling chamber 16 for the installation of the water-receiving member or chamber 25 and its parts, we construct the body 15 with 5 a removable top 61 provided with insulating material and adapted to fit into the upper part of body 15 onto a shoulder 62, preferably formed on the inner wall 18 of the cooling chamber or compartment 16, see 10 Fig. 1.

The body 15 may be provided with any suitable support, as, for example, legs 63 of sufficient number, which may be riveted or otherwise secured in place.

15 We have also shown the apparatus provided with a sanitary cup holding and dispensing device 64, see Fig. 1; the device being arranged to feed the cups, one at a time, upon proper manipulation of the 20 flange or slide-member 65. As this device forms the subject-matter of a separate application, a further detailed description thereof will not be entered into.

It is apparent from the foregoing description of our invention that drinking water or liquid may be dispensed from the original containers or bottles, which are closed by the stoppers 47, as soon as the bottles have been charged, thus obviating the possibility 30 of any foreign matter, dirt or bacteria getting into the water, as the outer wall or neck of the container or bottle cannot come into contact with the water or with the water-receiving portions of the apparatus, 35 as is clearly apparent.

It is further evident from the construction that the container or bottle may be put into place on the apparatus or displaced while still filled with water, without in any way 40 spilling the water, as the valve 48 will immediately become seated when the container or bottle 22 is lifted, thereby withdrawing tube 23 from the stopper 47.

The apparatus is so constructed that ready 45 access may be had to any part thereof; and when desired the water-receiving chamber 25 may be flushed out by means of the stand-pipe or tube 23, before the container or bottle 22 has been put into place; a suitable 50 hose or pipe being placed over the upper end of tube 23 and faucet 38 held open so as to allow the flushing water to flow out of the chamber or member 25.

We have shown and described what we 55 believe to be the simplest and best form of our invention, but the same may be modified in certain respects without, however, departing from the spirit of our invention, and we do not wish to be understood, therefore, as 60 limiting ourselves to the exact construction shown and described.

What we claim is:—

1. An apparatus of the class described, comprising a cooling chamber, a holding member arranged in the upper part of said

chamber, a liquid-receiving member arranged in said chamber and provided with a reduced upwardly presented portion arranged to extend into said holding member, a container or bottle having its orifice with- 70 in said holding member, and means arranged in the orifice of the container or bottle adapted to normally close said orifice, said means being arranged to receive said upwardly presented portion to effect communication with the liquid-receiving member. 75

2. An apparatus of the class described, comprising a tank provided with an upper and a lower compartment, the upper compartment constituting a cooling chamber 80 while the lower compartment constitutes a storage chamber, the cooling chamber being provided with a drain or discharge extending into the lower compartment, a removable cup secured about the outlet end of 85 said drain so as to provide a water-seal therefor, a drip-receiving member secured to the tank-exterior and provided with a discharge extending into said lower compartment, a water-receiving member removably 90 mounted in said cooling chamber in spaced relation with the side walls and bottom thereof, said member being provided with an inlet tube presented upwardly, a cup-member secured in the upper part of the 95 cooling chamber and arranged to receive said inlet tube, a water-container invertedly mounted in said cup-member and receiving the upper end of said inlet tube, and means for withdrawing the water from said water- 100 receiving member and for admitting air into the upper part thereof.

3. An apparatus of the class described, comprising a cooling chamber provided with a drain or discharge, means for automatically sealing said drain, a liquid-receiving member located in said chamber and provided with an upwardly presented inlet tube or spout, a container or bottle removably mounted above said member and provided 110 with an orifice arranged to receive said inlet spout or tube, means for effecting a liquid-tight connection between the spout or tube and said container or bottle and to automatically close said orifice when the inlet spout 115 or tube is withdrawn, and means for withdrawing liquid from said member.

4. An apparatus of the class described, comprising a receptacle provided with an upper chamber and a lower chamber, the upper chamber being adapted to constitute a cooling chamber while the lower chamber constitutes a storage chamber, a liquid-receiving member removably mounted in the cooling chamber and provided with an upwardly disposed inlet tube, the top of the cooling chamber being provided with a cup-member adapted to receive and be secured to said inlet tube, and a liquid containing bottle invertedly seated in said cup-member 120 125 130

and provided with resilient means in the orifice thereof adapted to receive said inlet tube and effect fluid-tight connection therewith, said resilient means being provided with a spring-controlled closure member.

5. An apparatus of the class described, comprising a cooling chamber provided with a container or bottle-holding member, a container or bottle invertedly seated in said member, a liquid-receiving receptacle in said cooling chamber, provided with an upwardly presented portion adapted to extend through said holding member and into the orifice of the container or bottle, and means 10 arranged at the orifice of the container or bottle for automatically closing said orifice, said means being adapted to receive the upwardly presented portion of said liquid-receiving receptacle so as to affect said means 15 20 and permit the liquid to flow from the container or bottle into the liquid-receiving receptacle.

6. An apparatus of the class described, comprising a tank provided with an upper 25 and a lower compartment, the upper compartment having insulated walls and constituting a cooling chamber, while the lower compartment constitutes a storage chamber, the lower compartment being provided with 30 a door slidably mounted within the outer

wall thereof, a drip-receiving member secured to the wall-exterior of the lower compartment and arranged to drain into said compartment, the upper compartment being provided with a drain-tube leading into the 35 lower compartment, a water-receiving receptacle mounted in said cooling chamber in spaced relation with the side walls and bottom and provided with a draw-off cock or faucet arranged on the cooling chamber exterior 40 and above said drip-receiving member, the water-receiving receptacle being provided with an upwardly disposed inlet tube, the upper part of the cooling chamber being provided with a cup-member arranged 45 to receive said inlet tube and be secured thereto, an inverted bottle or liquid-holder seated in said cup-member and receiving the upper end of said inlet tube, and means 50 removably secured in the orifice of said bottle or liquid-holder adapted to form liquid-tight connection with said inlet tube and prevent escape of liquid from said bottle.
